UNITED STATES PATENT OFFICE.

JOSEPH B. EDWARDS, OF JERSEY CITY, NEW JERSEY, ASSIGNOR OF ONE-FOURTH TO
TIDE WATER OIL COMPANY, OF BAYONNE, NEW JERSEY, A CORPORATION OF NEW
JERSEY.

OIL-DISTILLING APPARATUS.

1,277,884.

Specification of Letters Patent. Patented Sept. 3, 1918.

Application filed September 19, 1916. Serial No 120,929.

To all whom it may concern:

Be it known that I, JOSEPH B. EDWARDS, a citizen of the United States, and resident of Jersey City, in the county of Hudson and State of New Jersey, have invented certain new and useful Improvements in Oil-Distilling Apparatus, of which the following is a specification.

My invention relates to pressure distilling apparatus for cracking petroleum or its higher boiling point fractions, to obtain lighter products, *e. g.* gasoline, and is more particularly concerned with that branch of the art of pressure distillation wherein a bulk of heated oil is kept under a pressure of the vapors, as in a shell still with or without tubes. In these processes pressures up to and even greater than a hundred pounds are employed, and the resulting fire hazard has led to the adoption of certain precautions to prevent burning out the bottoms of the stills and discharging their contents directly into the fire. Such provisions, however, are of no effect in event 25 of a break beyond the still, that is to say, in the vapor eduction or condensing system. Such system, or a portion thereof, is subject to the same high pressure condition as the still, and if a break occurs in this 30 part of the apparatus an immediate outrush takes place from the still through the intervening part of the system to the break, and thus to the atmosphere, where, the oil and vapors being at a temperature above 35 the flash point, immediate combustion takes place and is fed by the large supply in the still. In this way, not only the still initially affected but many others assembled in the same battery or vicinity may be destroyed. 40 Such conflagrations have occurred, with sacrifice of life as well as heavy property loss; and it is the object of this invention to overcome the serious danger thus presented. To this end shut-off means are provided at the still outlet for preventing the pressure in the still driving its contents through the eduction system to the atmosphere in event of a break occurring at some point therein. Such shut-off means may be 45 wholly automatic, moving to its seat as the result of the substantial difference in pressure at its opposite faces produced by the opening of the eduction system to the at-

mosphere, but, preferably, a semi-automatic mechanism is employed, the valve being self-seating under the pressure of the vapors or of a counterweight or motor, or both, and being normally restrained by a trigger, which can be withdrawn by an attendant through a control operable at a point of safety remote from the eduction system, the valve when once closed being held forcibly to its seat by the vapor pressure in the still. In this way an instantaneous and secure closing of the still can be effected, leaving only the vapors in the eduction system itself to be consumed, but without the danger of the shut-off valve becoming seated, when not desired, by an abnormal or sudden rise in pressure in the still, as may occur under certain conditions of firing, and which if the outlet then became sealed would cause the vapors to blow off through the relief valve regularly provided.

In the accompanying drawings:

Figure 1 is a semi-diagrammatic view illustrating a pressure distilling system with the invention embodied therein;

Fig. 2 is a vertical section through the vapor outlet and shut-off means, taken on the line 2-2 of Fig. 3;

Fig. 3 is a horizontal section on the line 3-3 of Fig. 2; and

Fig. 4 is a vertical section through the vapor outlet showing another embodiment of shut-off.

In Fig. 1 A represents a petroleum still of suitable form, having a vapor outlet at the top and toward the rear, from which leads the upwardly inclined vapor pipe B of large diameter, having a vertical neck D secured in the outlet, and at its upper end delivering the vapors to a pipe E of smaller diameter which conducts them to the top of an aerial condenser F, whence the distillate passes to a cooler coil G, and thence through running line H to receiving drum I, from which the gasoline or other distillate is drawn off past a high pressure needle regulating valve K to running tank J. This valve K, together with a valve L governing the escape of fixed gases from the receiving drum, are set to create the desired back pressure of the vapors in the system. The inclined vapor pipe, as is well known, is for the purpose of condensing and returning to

the still all products heavier than the desired distillate, and is constructed of the proper length and with the proper condensing surface for this purpose. In the foregoing apparatus, which is representative of those now in use, there is no means, except that provided in accordance with this invention, which is capable of shutting off the flow through the eduction system, until the point M is reached, between the aerial condenser and the cooler coil, where a gate valve N is inserted. This valve is not intended as a safety shut-off, and is indeed without practical value for such use, because the real danger of breakage lies in advance of this point, the said valve being merely to prevent the inferior distillate at the beginning of a run passing through and fouling the cooler coil, and thence passing into the receiving drum and so on to the rest of the system, such early distillate being instead switched through a valve R to a branch O, whence it passes to a place of disposal or to other apparatus not shown. Beyond these valves, that is to say in the cooler coil and subsequently, the oil is below its flash point, but between them and the still the expansion strains are severe, and even with swing joints there is always the possibility of some part, from the neck D onward, giving way, in which event there is a forcible escape of highly inflammable vapors and oil above the flash point, with the likelihood of the disastrous consequences above indicated.

To overcome this condition I provide a safety shut-off, at the source, so that the whole eduction and condensing system can be promptly cut off from the contents of the still in event of a rupture at any point in the system. The form of shut-off shown in Fig. 4 and designated P' can be employed, the same comprising a hinged flap valve 1 adapted to close against an inclined seat 2 formed on the lower end of a curved continuation 3 of the neck D within the top of the still. This constitutes an automatic check valve, which normally stands open but is closed by the pressure in the still if the pressure in the vapor pipe falls by reason of a break in this conduit or elsewhere in the pressure eduction system. Since this type of valve when once closed would continue to be held tightly to its seat, it becomes necessary in order to enable it to open again to provide a relieving line 4, having a normally closed valve 5 therein, which when opened will equalize pressures at opposite sides of the valve member 1.

For the reasons heretofore stated, however, I prefer to use a shut-off under the control of an attendant, of which the form which I regard as most suitable is shown in Figs. 1, 2 and 3 and designated generally P. In accordance with this construction a

valve disk 10 is mounted for vertical movement within the still to coöperate with a suitable seat 11 on the lower inwardly-projecting end of the vapor neck D. This is suspended by a valve stem or rod 12, the upper end of which is pivoted loosely on a pintle 13 carried by the end of an arm 14 within the neck, which arm in turn is mounted upon a rock-shaft 15 journaled in bearings 16 and 17 in the neck. At one end this shaft passes through the wall of the neck, where a tight joint is preserved by a stuffing-box 18, and with the outer portion of the shaft is connected a weight arm 19, which is normally sustained by a trigger 20. A wire 21 passes from this trigger to the front of the still and thence down to a box 22 located at a convenient point and adapted to afford access to the end of the wire upon breaking a glass pane, after the manner of a fire-alarm box. In case of a break in the eduction and condenser system it is the work of a moment to pull this wire, whereupon the shut-off valve closes immediately and is held closed by the still pressure. Manifestly the counterweighting of the valve disk may be sufficient to counterbalance or to overbalance the weight of this part.

Attention may be called to certain details of the construction of the valve. It will be noted that the provision of the rock-shaft 15 obviates a sliding stuffing-box and permits the employment of the tighter rotary joint instead. The arm 14 is removably mounted on this shaft by a pin 23, the hub of the arm through which this pin passes extending to the bearing 16 so as to hold the shaft and arm in position. The loose connection of the upper end of the rod 12 with the pintle 13 enables the rod to be disengaged therefrom by a tilting movement of the rod and valve when a pin 24 is removed. The valve disk can then be removed, inwardly of the still, as for cleaning. In order to enable the valve stem to be left thus free, and to avoid the presence of carbon-accumulating guides inside the neck of the vapor pipe, I provide guide lugs 25 for the periphery of the disk, these lugs projecting downward below the valve seat at spaced points and having notches 26 at the seat to prevent carbon becoming packed at these corners and constituting an obstacle to tight closing.

It is to be understood that various other forms of quick-closing shut-off valves may be employed. I would also point out that, while the apparatus selected for illustration is one in which the pressure of the vapors is maintained up to and including the region where the gasoline or other desired product is condensed, it is not essential to the invention that this condensation take place under pressure, since the pressure can be relieved at the upper end of the vapor

pipe if desired, through the provision of a suitable valve, condensation then taking place at atmospheric or ordinary pressure.

It will further be understood that any excessive pressure which might be created in the still after the closing of the shut-off valve will be relieved through a safety valve ⁸, of the kind regularly provided in these stills.

10. What I claim as new is:

1. In apparatus for pressure cracking of petroleum or its higher boiling point fractions, the combination with a pressure oil still comprising a shell having a single vapor outlet at the top, a pressure vapor eduction and condensing system connected with said outlet, and means for maintaining a substantial back pressure of the vapors in the eduction system and still, of shut-off means located in the top of the still at the source of the pressure eduction system for cutting off forcible rush of the highly heated contents of the still through said system to the atmosphere in event of a break beyond the still, an attendant's control device, and connections for securing the closing of the shut-off means.

2. In apparatus for pressure cracking of petroleum or its higher boiling point fractions, the combination with a pressure oil still having a vapor outlet, a vapor eduction and condensing system, and means connected therewith for maintaining a substantial back pressure of the vapors, of a shut-off valve within the still for closing said outlet against the passage of oil or vapors into the eduction system in event of rupture beyond the still, said valve being constructed to be then held to its seat by the pressure of the vapors in the still.

3. In apparatus for pressure cracking of petroleum or its higher boiling point fractions, the combination with a pressure oil still comprising a shell having a single vapor outlet at the top, a long upwardly inclined vapor pipe connected with said outlet, and means beyond the vapor pipe for maintaining a substantial back pressure therein and in the still, of an upwardly movable quick-acting shut-off valve co-operative with the vapor outlet and having an ample face exposed to the still pressure, means normally holding the valve open, and an attendant's device and connections for controlling the quick-acting shut-off valve.

4. In apparatus for pressure cracking of petroleum or its higher boiling point fractions, the combination with a pressure still and its vapor outlet and pressure eduction system, of automatically-closing shut-off means for said outlet comprising a valve exposed to the vapor pressure tending to hold it against the outlet when closed, a trigger normally holding the valve open,

and an operator's control remote from the eduction system for releasing said trigger.

5. In apparatus for pressure cracking of petroleum or its higher boiling point fractions, the combination with a pressure still and its vapor outlet and pressure eduction system, of automatically-closing shut-off means for the outlet comprising a vertically-guided disk valve in the upper part of the still acted upon by the pressure therein tending to hold it against the outlet when closed, means normally holding the valve open, and means operable at a distance from the eduction system for causing the valve to close.

6. In apparatus for pressure cracking of petroleum or its higher boiling point fractions, the combination with a pressure still and its vapor outlet and pressure eduction system, of automatically-closing shut-off means for the outlet comprising a vertically-guided disk valve in the upper part of the still acted upon by the pressure therein tending to hold it against the outlet when closed, a valve stem, a weight connected with the valve stem tending to close the valve, a trigger normally supporting the weight, and means for withdrawing the trigger.

7. In apparatus for pressure cracking of petroleum or its higher boiling point fractions, the combination with a pressure still having a vapor outlet, a vapor pipe leading from the outlet, a disk valve within the upper part of the still beneath the outlet and having a stem extending upward into the vapor pipe, a transverse rock-shaft journaled in the vapor pipe and passing at one end through the wall of the same, an arm on the rock-shaft within the pipe connecting with the valve stem, and operating means connected with the rock-shaft outside the pipe.

8. In apparatus for pressure cracking of petroleum or its higher boiling point fractions, the combination with a pressure still having a vapor outlet provided with a valve seat and a pressure vapor pipe, of a valve disk within the top of the still movable upward against said seat, guides for the periphery of the valve disk projecting downward below the valve seat at spaced points, a transverse rock-shaft journaled in and projecting at one end from the vapor pipe and provided therein with an arm, a free rod connecting the valve disk with said arm, and means connected with the exterior portion of the rock-shaft for controlling the valve.

9. In apparatus for pressure cracking of petroleum or its higher boiling point fractions, the combination with a pressure still having a vapor outlet provided with a valve seat and a pressure vapor pipe, of a valve disk within the top of the still movable upward against said seat, guides for the periphery of the valve disk projecting down-

ward below the valve seat at spaced points, a transverse rock-shaft journaled in and projecting at one end from the vapor pipe and provided therein with an arm, means separately connecting said disk with the arm whereby the disk may be removed inwardly of the still, and valve-controlling means connected with the exterior portion of the rock-shaft.

- 10 10. In apparatus for pressure cracking of petroleum or its higher boiling point fractions, the combination with a pressure still having a vapor outlet provided with a valve seat and a pressure vapor pipe, of a shut-off valve comprising a valve disk within the top of the still movable upward against said seat, and guides for the periphery of the valve disk projecting downward below the seat at spaced points, said guides being notched at the seat to prevent accumulation of carbon at these points.

11. In apparatus for pressure cracking of petroleum or its higher boiling point fractions, the combination with a pressure oil still having a vapor outlet opening in its top, and a pressure vapor eduction system including a vapor pipe connected with the outlet opening of the still, of a valve seat adjacent the inlet of the vapor pipe, a valve movable toward and from the valve seat and adapted to be held thereto by the pressure of the vapors when closed following a rupture in the external pressure system, and external control means for causing the closing of the valve.

12. In apparatus for pressure cracking of petroleum or its higher boiling point fractions, the combination with a pressure oil still having a vapor outlet opening in its top, and a pressure vapor eduction system including a vapor pipe having a neck extending through said outlet opening into the still, of an annular valve seat on the lower end of said neck, a vertically guided disk beneath the valve seat having a rod extending upward into the neck and adapted to be raised against the seat, there to be held by the pressure of the vapors in event of rupture in the external system, and external control means connected with said rod and having its connection passing through the wall of the vapor pipe.

13. In apparatus for pressure cracking of petroleum or its higher boiling point fractions, the combination with a pressure oil still, and a pressure vapor eduction system leading therefrom, of a valve seat adjacent the inlet of said eduction system, a valve movable toward and from said seat and adapted to be held against the same by the pressure of the vapors in the still in event of rupture in the external system, means for

holding the valve open away from the seat, and external control means operatively connected with the valve to cause closing of the same.

14. In apparatus for pressure cracking of petroleum or its higher boiling point fractions, the combination with a pressure still having a vapor outlet opening at the top, and a pressure eduction system comprising a vertical neck connected to said outlet opening and with an inclined vapor pipe, of an annular valve seat at the lower end of said neck, a vertically-movable normally-open shutoff valve disk in the upper part of the still coöperative with said valve seat, and means for securing the closing of the valve comprising parts extending within the neck and exteriorly thereto and terminating in an attendant's device.

15. In apparatus for pressure cracking of petroleum or its higher boiling point fractions, the combination with a pressure still having a vapor outlet in its top, and a pressure eduction system leading therefrom, of a horizontally disposed annular valve seat in the still at the entrance to the vapor outlet, a vertically-movable normally-open shutoff valve disk coöperative with said seat, guides for the periphery of said disk extending downward below the seat, and means extending from the disk within the outlet and connected with external mechanism for securing the operation of the valve.

16. In apparatus for pressure cracking of petroleum or its higher boiling point fractions, the combination with a pressure oil still comprising a shell having a single vapor outlet, a pressure eduction system leading therefrom, and means for maintaining a substantial back pressure in the eduction system and still, of a normally-open shut-off valve coöperative with said vapor outlet for cutting off forcible rush of the highly heated contents of the still through the pressure eduction system to the atmosphere in event of a break beyond the still, an attendant's device, and means whereby closing of the valve is controlled by said device.

17. In apparatus for pressure cracking of petroleum or its higher boiling point fractions, the combination with a pressure oil still comprising a shell having a vapor outlet opening in the top, a pressure eduction system comprising a vertical neck secured to the outlet opening, and means for maintaining a substantial back pressure in the vapor eduction system and still, of a valve seat on said neck, and a shut-off valve movable toward and from said seat and adapted when closed to be held thereto by the pressure in the still.

JOSEPH B. EDWARDS.
